Primary Examiner — Thomas Johannes(74) *Attorney, Agent, or Firm* — Frost Brown Todd LLC(57) **CLAIM**

The ornamental design for a food container, as shown and described.

DESCRIPTION

FIG. 1 is a top perspective view of a food container, showing our new design;

FIG. 2 is a bottom perspective view thereof;

FIG. 3 is a front elevation view thereof;

FIG. 4 is a back elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken line portion of the figure drawings is included to show unclaimed subject matter only and forms no part of the claimed design.
